BY MESNE ASSIGNMENTS, TO PAWLING AND HARNISCHFEGER COMPANY, OF WEST
MILWAUKEE, WISCONSIN, A CORPORATION OF WISCONSIN.

HOISTING AND CONVEYING APPARATUS.

992,307.

Specification of Letters Patent. Patented May 16, 1911.

Application filed October 30, 1909. Serial No. 525,458.

To all whom it may concern:

Be it known that we, HENRY WEICKEL and REGINALD K. MORSE, citizens of the United States, residing at Milwaukee, in the county 5 of Milwaukee and State of Wisconsin, have invented certain new and useful Improvements in Hoisting and Conveying Apparatus, of which the following is a specification, reference being had to the accompanying 10 drawing, forming a part thereof.

This invention relates more particularly to hoisting and conveying apparatus adapted to run on an overhead track or way. Its main objects are to facilitate picking up, 15 conveying from place to place and depositing lumber and other materials or articles, and generally to improve the construction and operation of apparatus for this purpose.

It consists in the construction, arrangement and combination of parts as hereinabove particularly described and defined in the claims.

In the accompanying drawing like characters designate the same parts in the several figures.

Figure 1 is a side elevation of apparatus embodying the invention and specially designed for handling lumber and the like; Fig. 2 is an enlarged elevation as viewed 30 from the right with relation to Fig. 1 and a central section on the line 2--2, Fig. 3, of the lifting beam or head and the grapple connected therewith; and Fig. 3 is a plan view of the parts shown in Fig. 2.

Referring to Fig. 1, *a* is a trolley frame suspended by wheels *b* from an overhead track *c*, consisting of an I-beam or rail, *d* is a hoisting drum mounted in the under side of the frame *a*, and *e* is an electric motor, 40 also carried by said frame and adapted to operate said drum. *f* is another electric motor carried by said frame and connected by gears with one set of trolley wheels *b* for propelling the trolley along the track *c*. *g* is an operator's cage coupled to the trolley frame and suspended in like manner from the track *c* by wheels *h*.

Current for operating the electric motors is taken from a wire or conductor *i*, running 50 parallel with the track *c* by a contact wheel *j* carried by the suspension frame of the wheels *h*. The cage is provided with controllers *k* in the motor circuits.

A lifting beam or head *l* is provided ad-

jacent to its ends with sheaves *m*, and is suspended from the trolley by cables passing around said sheaves and attached at one end to the frame *a* and at the other end to the drum *d*. The lifting beam or head is provided with a grapple for picking up lumber and other material or articles to be hoisted and conveyed from place to place. In the present case the grapple is designed specially for handling lumber and the like, and consists, as shown more in detail in Figs. 2 and 3, of a frame *n* and two pairs of oppositely arranged hooks *o* fixed on the ends of parallel shafts *p*, which are journaled in the ends of said frame. To admit of turning the frame with the load suspended therefrom with relation to the lifting beam or head *l* for convenience in handling certain kinds of material, for example, lumber which it is or may be desirable for the purpose of economizing room, to take from and deposit in piles crosswise of the track and to unload from or load upon cars or wagons, or to carry parallel with the track, the frame *n* has a swivel connection with the beam *l*. As shown in Figs. 2 and 3, this swivel connection comprises inner and outer bearing rings *q* and *r*. The inner ring *q*, which may be made in one piece, is formed or provided with upwardly extending attachment plates *s*, which are fastened to the side members of the beam *l*, and are connected by cross webs *t*. The outer ring *r*, which fits over and surrounds the ring *q*, is for the purpose of assembling, made in two parts, which are flanged on the outside and bolted together and formed with lugs *r'* which are bolted to cross pieces of the frame *n*, as shown in Figs. 2 and 3. To facilitate turning the frame *n* with the load suspended therefrom by the hooks *o*, the rings *q* and *r* are formed with opposing ball races, in which balls *u* are interposed as shown in Fig. 2.

For operating the grapping hooks *o*, which in the present case are turned outwardly into operative position as shown by full lines in Fig. 2, the shafts *p* are provided with inwardly extending arms *v*, which are pivotally connected at their inner ends with a pin *w*, which is swiveled in a vertically movable sheave block *x*. The sheave block *x* is guided and held in the proper relation to the lifting beam or head *l* by the extended journal pin *y* engaging with the vertical

slots in the cross webs *t*, the pin being held against endwise displacement by collars *z*. An operating cable *2* attached at one end to the hoisting drum *d*, is looped through the block *w* around the sheave therein and passes upwardly therefrom over a sheave *3* mounted on the frame *a* and thence to and around a drum *4* in the operator's cage *g*, a weight *5* being attached to its free end to take up slack and to afford a sufficient bite on the drum *4* to enable the latter, when turned, to swing the hooks *o* inwardly, as indicated by dotted lines in Fig. 2. The drum *4* may be provided as shown, with a crank *6* for taking up or shortening the cable *2* and swinging and holding said hooks out of operative position, or this may be accomplished by pulling down on the weight or on the cable itself. When released the hooks gravitate into operative position, as shown by full lines in Fig. 2, the weight *5* being insufficient to counterbalance them.

To lock and hold the frame *n* with the hooks *o* in the desired positions with relation to the lifting beam or head *l* and the track *c* on which the trolley travels, the inner bearing ring *q* is formed or provided on its outer side with keepers *7*, having sockets or recesses, and a bevel or incline on each side thereof, and a spring actuated radial latch bolt *8* guided in the outer ring *r* and in one side of the frame *n* is adapted to ride over the bevels or inclines on the keepers into engagement with the sockets or recesses there-
in when the frame *n* is turned with relation to the beam or head *l* from one position to another. The latch bolt *8* is pivoted at its outer end to an arm *9* on a rocker shaft *10*, which is mounted on the adjacent side member of the frame *n* and is provided at its outer end with a double arm *11* having eyes at the ends as shown in Fig. 1, so that the operator in cage *g* can reach and turn it with a hook.

The construction and arrangement of the grapple hooks may be varied within wide limits to adapt the device for handling different materials or articles, and for some purposes the swivel connection between the grapple and the lifting beam or head *l* may be dispensed with.

In handling lumber for which the apparatus as shown is specially designed, where the lumber is arranged in piles on cross supports *12* below and transversely to the overhead track *c* on which the trolley travels, the apparatus operates as follows: To pick up a load, the trolley having been brought to and stopped in a position directly over it, the hooks *o* being swung inward into the position indicated by dotted lines in Fig. 2 and held in that position, are lowered with the beam or head *l* on opposite sides of the pile, and between the protruding ends 65 of the supports *12*. When the points of the

hooks have descended below said cross supports, the motor *e* is stopped and the cable *2* is released or paid out, thus permitting the hooks *o* to swing outwardly into operative position underneath and against said cross supports. The load is then lifted by the operation of the motor *e* to a sufficient elevation to clear obstructions in the way to the place of deposit, the hook operating cable *2* being wound upon the drum *d* simultaneously with and at the same rate as the hoisting cables which pass around the sheaves *m*. In transporting the load from one place to another, it may be necessary or desirable in order to clear an obstruction, or for some other reason, to carry it in a position parallel with the track *c*, or it may be necessary or desirable to deposit the load in a different position from that which it first occupied. In either case the operator reaching from the cage with a hook, turns the arm *11*, withdraws the latch bolt *8* from the keeper *7* with which it engages, and by pulling or pushing on the hook still engaged with the arm *11* turns the frame *n* with the load suspended therefrom around the ring *q* into the desired angular position with relation to the lifting frame or head *l*, which is always carried parallel with the track *c*. The load having been conveyed to the point where it is to be deposited, is lowered into place, leaving the protruding ends of the cross pieces *12* and the hooks engaging therewith, clear and free. The beam or head *l* being lowered sufficiently to take the weight of the load off from the hooks, they are swung inwardly as indicated by dotted lines in Fig. 2, by the operator pulling in or shortening the cable *2*, as hereinbefore explained. The grapple frame and hooks are then drawn up with the lifting beam or head *l* above the load, which has been deposited, and said frame, if desired, may be turned back to its original position or into a corresponding position, in which it will be automatically locked by the bolt *8* springing into engagement with one of the keepers *7*.

Various changes in the details of construction and arrangement of parts of the apparatus may be made in the adaptation of the apparatus for handling various kinds of materials and articles without departing from the principle of the invention.

We claim:

1. The combination of hoisting mechanism, a lifting head connected by a cable with said hoisting mechanism, a grapple carried by said head, a cable having a looped connection with said grapple and connected at one end with said hoisting mechanism so as to be wound and unwound simultaneously with the winding and unwinding of the hoisting cable, and means for taking up and paying out the other end of the grapple cable.

2. The combination of hoisting mechanism, a lifting head connected by a cable with said hoisting mechanism, a grapple having a swivel connection with said head, a cable having a looped connection with said grapple and connected at one end with said hoisting mechanism, and means for taking up and paying out the other end of the grapple cable. 5
- 10 3. The combination of a trolley provided with hoisting mechanism, a lifting head movably connected with said hoisting mechanism, a grapple carried by said head, a cable having a slip loop connection with said grapple and connected with said hoisting mechanism, so as to be taken up and paid out according to the vertical movement of said head, and means for taking up and paying out the other end of the grapple cable independently of the hoisting mechanism. 15
4. The combination of a trolley provided with hoisting mechanism, a lifting head movably connected with said hoisting mechanism, a grapple having a swivel connection with said head, a cable having a slip loop connection with said grapple and connected with said hoisting mechanism, and means for taking up and paying out the other end of the grapple cable independently of the hoisting mechanism. 20
5. The combination of hoisting mechanism comprising a drum and motor for turning the drum, a lifting head provided with 35 sheaves, cables looped around said sheaves and attached at one end to said drum and at the other to the drum frame, a grapple consisting of opposing hooks pivotally connected with said head, a block connected with said grapple hooks and adapted by its vertical movement to turn said hooks on their pivots, a cable loosely looped through said block and connected at one end with said drum, and means for taking up and 40 paying out the other end of the grapple operating cable independently of the hoisting mechanism. 45
6. The combination of hoisting mechanism comprising a drum and motor for turning the drum, a lifting head provided with sheaves, cables looped around said sheaves and attached at one end to said drum and at the other to the drum frame, a grapple consisting of a frame having a swivel connection with said head and opposing hooks pivotally connected with said frame, a vertically movable sheave block guided in the lifting head and having a swivel connection with said hooks concentric with the swivel 50 connection between the lifting head and grapple frame, a cable passing around the sheave in said block and attached at one end to said drum, and means for taking up and paying out the other end of the grapple operating cable independently of the drum. 55
7. The combination with hoisting mechanism comprising a drum and a motor for turning the drum, of a lifting head provided with sheaves, cables passing around said sheaves and connected with said drum, a grapple comprising a frame having a swivel connection with said head and hooks pivotally connected with said frame, a vertically movable block guided in said head and having a pivot and swivel connection with said hooks, a cable loosely looped through said block and connected at one end with said drum, means for taking up and paying out the other end of said cable independently of said drum, and means for locking the grapple frame in different angular positions relative to the lifting head. 70
8. The combination with hoisting mechanism comprising a drum and a motor for turning the drum, of a lifting head connected by cables with said drum and provided with a central bearing ring, a grapple comprising a frame provided with a central bearing ring adapted to turn horizontally on the other ring, and hooks pivotally connected with said frame, a vertically movable block guided in said head and having a swivel connection with said hooks passing through the inner bearing ring, a cable looped through said block and connected at one end with said drum, and means for taking up and paying out the other end of said cable independently of the drum. 80
9. The combination with hoisting mechanism, of a lifting head connected with said hoisting mechanism and provided with a central bearing ring, a frame provided with a central bearing ring fitting over and adapted to turn on the other bearing ring, hooks pivotally connected with said frame, a vertically movable block guided in said head and having a swivel connection with said hooks passing through the inner bearing ring, a cable looped through said block and connected at one end with said hoisting mechanism, means for taking up and paying out the other end of said cable independently of the hoisting mechanism, and a locking bolt movable radially through the outer bearing ring into and out of engagement with the inner bearing ring. 90
10. The combination with a trolley adapted to travel on an overhead track and provided with a hoisting drum and with motors for propelling the trolley and for turning said drum, of a lifting head connected by cables with said drum, opposing hooks pivotally connected with said head and provided with operating arms, a block connected with said arms and movable vertically with relation to said head, a cable looped through said block and connected at one end with said drum, a weight attached to the other end of said cable, and a drum around which said cable passes above said weight. 110

11. The combination with a trolley adapted to travel on an overhead track and provided with a hoisting drum and a motor for turning the drum, a lifting head connected with said drum by cables, hooks pivotally connected with said head, a block connected with said hooks and movable vertically with relation to said head, a cable looped through said block and connected at one end with 5 said drum, a weight attached to the other end of said cable, a guiding sheave over which said cable passes above said block and adjacent to said drum, and a drum around which said cable passes above and adjacent 10 to said weight.
12. The combination with a trolley adapted to travel on an overhead track and provided with a hoisting drum and with motors for propelling the trolley and turning 15 the drum and an operator's cage connected with said trolley, of a lifting head connected by cables with the drum, a grapple frame having a swivel connection with said head, hooks pivotally mounted in said frame, a 20 block having a swivel connection with said hooks, a cable looped through said block and connected at one end with said drum, the other end passing over a sheave on the trolley frame adjacent to said drum and thence 25 to the operator's cage, a latch bolt for locking the grapple frame in different angular positions relative to the lifting head, and a rocker shaft having an arm connected with 30 said bolt and an operating arm accessible 35 from said cage.
13. The combination of hoisting mechanism, a lifting beam connected therewith and provided with a central horizontal bearing ring, a frame having a central horizontal bearing ring rotatably connected with the 40 other ring, parallel horizontal rocker shafts mounted in said frame and each provided with depending outwardly directed hooks and with an inwardly extending arm, and an operating connection passing through 45 said rings and attached to the inner ends of the arms on said rocker shafts.
14. The combination of hoisting mechanism, a lifting head connected therewith, a grapple having a swivel connection with 50 said head, and means for locking said grapple in a certain position with relation to said head.
15. The combination with a hoisting drum, a lifting head connected with said drum by 55 cables and provided with a central bearing ring, a grapple comprising a pivoted hook and provided with a bearing ring forming with the other ring a swivel connection between said head and grapple, and a hook operating connection passing through said rings.

In witness whereof we hereto affix our signatures in presence of two witnesses.

HENRY WEICKEL
REGINALD K. MORSE.
